UNITED STATES PATENT OFFICE.

ALVA M. COLT, OF BATAVIA, NEW YORK.

DESIGN FOR A C-CLAMP BODY.

41,287.

Specification for Design.

Patented Apr. 4, 1911.

Application filed February 6, 1911. Serial No. 607,000. Term of patent 14 years.

To all whom it may concern:

Be it known that I, ALVA M. COLT, a citizen of the United States, residing at Batavia, in the county of Genesee and State of New York, have invented a new, original, and ornamental Design for C-Clamp Bodies, of which the following is a specification.

The accompanying drawing represents in Figure 1 a side elevation, and in Fig. 2 a plan view of a C-clamp body showing the design.

The main feature of the design consists in the ornamental curved ribs on the oppo-

site sides of the C-shaped clamp body. These ribs diverge forwardly from the middle portion of the rear edge of the body into the upper and lower arms thereof, merging into the outer edges of said arms.

I claim:

The ornamental design for a C-clamp body, as shown and described.

ALVA M. COLT.
